UNITED STATES PATENT OFFICE.

EGBERT H. GOLD AND ELMER W. RIETZ, OF CHICAGO, ILLINOIS; SAID RIETZ ASSIGNOR
TO SAID GOLD.

STEAM-HEATING SYSTEM.

1,241,620.

Specification of Letters Patent.

Patented Oct. 2, 1917.

Application filed September 3, 1915. Serial No. 48,903.

To all whom it may concern:

Be it known that we, EGBERT H. GOLD and ELMER W. RIETZ, citizens of the United States, residing at Chicago, in the county of Cook and State of Illinois, have invented certain new and useful Improvements in Steam-Heating Systems, of which the following is a specification.

Our invention relates to a steam heating system and, more specifically, to a steam heating system for railway cars comprising a valve for shutting off the radiating element from the supply and controlling means of the system, and at the same time opening a drainage port through which the water of condensation in the radiating element may discharge. If water of condensation is allowed to accumulate in the heating coils, for example, of a railway car heating system there is great danger that the coils may be frozen up causing considerable damage and inconvenience. The primary object of our invention is to so construct the shut-off valve in a system of this character that the discharge of water of condensation is facilitated and made more certain than in steam heating systems heretofore used.

More specifically our invention provides an improvement upon the four-way valve forming a part of the car heating system described and claimed in the patent to Egbert H. Gold No. 868,772, granted October 22, 1907 for low pressure fluid heating system, whereby the danger that the water of condensation may be prevented from discharging through the formation of a vacuum in the radiating pipes is entirely obviated.

The invention has for a further object to provide a four-way valve of the improved construction to be hereinafter described and claimed.

The invention is illustrated, in a preferred embodiment, in the accompanying drawings wherein—

Figure 1 is a fragmentary view, in perspective, of a low pressure or vapor heating system provided with a shut-off valve constructed in accordance with the invention.

Fig. 2 is a sectional plan of the cut-out valve.

Fig. 3 is a vertical sectional view thereof taken on line 3—3 of Fig. 2, and

Fig. 4 is a fragmentary sectional plan showing the valve body in a different position from that shown in Figs. 2 and 3.

Like characters of reference designate like parts in the several figures of the drawings.

Referring to the drawings, A is the radiating element consisting, in the installation shown, of a continuous coil of radiating pipes, B the train pipe, C, C' the supply pipe of the radiating coil, D a discharge pipe leading from the radiator, E a controlling device or vapor regulator which is interposed between the two sections C, C' of the supply pipe and to which the discharge pipe D leads, and F a four-way shut-off valve the purpose of which is to either direct the steam from the supply pipe into the radiating element and from the radiating element to the discharge pipe, or to short circuit the steam from the supply pipe directly to the discharge pipe and cutting out the radiating coil and placing the inlet and outlet ends A', A² thereof in communication with each other. The vapor regulator E is of familiar construction and operates by means of a valve interposed between sections C, C' of the supply pipe and a thermostat under influence of the medium discharged through discharge pipe D to maintain the steam in the radiator A, when the latter is in service, at substantially atmospheric pressure. When the four-way valve F is manipulated to cut out the radiator the steam is short circuited to the thermostat of the controlling device E in just sufficient quantities to keep the controlling device from freezing up as is well known in systems of this type.

The four-way valve F is constructed as follows: 10 is a casing provided with interior webs 11, 12, 13 and 14, dividing the casing into a chamber 15 communicating with a supply pipe, a chamber 16 with which the inlet end A' of the radiator is connected, a chamber 17 to which the outlet end A² of the radiator leads, and a chamber 18 communicating with the discharge pipe D. 19 is a valve body arranged in the space between the aforesaid interior webs and formed at the top with a disk 20 and at the bottom with a disk 21. The valve body is provided with a stem 22 extending through a bonnet 23 on the top of casing 10 and provided with a handle 24, a spring 25 being preferably interposed between the bonnet and the upper disk 20. A drainage pipe 26 is tapped into the under side of the valve 110

casing beneath the lower disk 21 of the valve body and the bottom of the casing is formed with a port 27 with which a port 28 in the disk 21 registers when the valve body 5 is in its short circuiting position. The drainage port 27, 28 is designed to permit the outflow of water of condensation from the radiating coil when steam is shut off from the latter, that is, when the valve body 10 19 of the four-way valve stands in the position shown in Figs. 2 and 3. Experience has proven, however, that the formation of a vacuum in the radiating coil due to the condensation of the steam tends to check the 15 outflow of the water through a drainage port of this character. To overcome this the valve body is formed with a vertical port 29 communicating with the radiator side of the valve by a short branch port 30 and with 20 the drainage pipe 26 by an arcuate branch port 31 in the lower disk 21, the latter being adapted to register with a port 32 in the bottom of the valve casing when the valve body is turned to its short circuiting position. 25 Thus an air inlet duct is provided which opens into the radiator side of the valve preferably at the top thereof. This prevents the formation of a vacuum in the radiator pipes so that the water of condensation which accumulates therein may outflow freely through the discharge port 27, 28.

While we have described our invention in a certain preferred embodiment, it is realized that changes might be made in the form 35 and construction of the apparatus without departure from the principles of the invention. Therefore we do not wish to be understood as intending to limit the invention to the particular devices, constructions 40 and arrangements shown and described except so far as the claims are specifically so limited.

We claim:

1. In a steam heating system, the combination of a radiating element; a supply pipe; a discharge pipe; and a valve comprising a four-chambered casing, two of the chambers of which communicate with the radiating element and the other two with 45 said supply and discharge pipes respectively, and a valve body revolvably arranged between said chambers so that it may assume positions at right angles to each other to either direct the steam from the supply pipe

through the radiator to the discharge pipe 55 or to short circuit the steam from the supply pipe directly to the discharge pipe and put the chambers open to the radiator in communication with each other; said valve body being formed with an upright web and a bottom disk each provided with a port opening into the radiator side of the valve casing the port in the web at a point near the top of the web and the bottom of the casing being formed with ports open to the 60 atmosphere with which the ports in said valve body are adapted to register, respectively, only when the valve body is in the short circuiting position.

2. In a steam heating system, the combination of a radiating element having an inlet and an outlet, means for introducing steam into said radiating element through the inlet, and means for closing said inlet and outlet and for providing a drainage 70 port from the radiator and an air inlet port leading into the same at a level above the drainage port.

3. In a steam heating system, the combination of a radiating element; a supply 80 pipe; a discharge pipe; and a valve comprising a four-chambered casing, two of the chambers of which communicate with the radiating element and the other two with said supply and discharge pipes, respectively, and a valve body revolvably arranged between said chambers so that it may assume positions to direct the steam either from the supply pipe through the radiator and to the discharge pipe, or to short circuit the steam from the supply pipe directly to the discharge pipe and put the chambers open to the radiating element in communication with each other; said valve body being provided with a bottom disk perforated to form a water discharge port and with an upright web having an air inlet port opening through the side of the same and through said bottom disk, and the bottom of the casing being formed with two ports with which the ports in the valve body are brought into register when said valve body is in its short circuiting position; the ports in the valve body being arranged so as to open on the radiator side of the valve 95 when the radiator is closed thereby.

EGBERT H. GOLD.
ELMER W. RIETZ.
